UNITED STATES PATENT OFFICE.

SAMUEL WALL, OF HARRISBURG, ILLINOIS.

RAILROAD-TIE.

1,106,482.

Specification of Letters Patent. Patented Aug. 11, 1914.

Application filed November 8, 1913. Serial No. 799,927.

To all whom it may concern:

Be it known that I, SAMUEL WALL, citizen of the United States, residing at Harrisburg, in the county of Saline and State of Illinois, have invented certain new and useful Improvements in Railroad-Ties, of which the following is a specification, reference being had therein to the accompanying drawing.

10 This invention relates to railroad ties and means for securing rails thereto and has for its object the production of a simple and efficient means which will efficiently support the rail so as to prevent the rail from becoming accidentally detached from the tie.

Another object of the invention is the production of a simple and efficient chair or rail engaging member for supporting the rail in engagement with a tie or stringer.

20 With these and other objects in view this invention consists of certain novel combinations, constructions, and arrangements of parts as will be hereinafter fully described and claimed.

25 In the accompanying drawings:—Figure 1 is a front elevation of the tie showing the chair and rails attached thereto. Fig. 2 is a section taken on line 2—2, of Fig. 1. Fig. 3 is a detail perspective view of the chair used in connection with the present invention. Fig. 4 is a transverse section through the tie showing a modified form of means for attaching a rail thereto from that illustrated in Figs. 1, 2 and 3. Fig. 5 is a front elevation of the tie partly shown in section of the structure shown in Fig. 4. Fig. 6 is a top plan view of the structure shown in Fig. 5. Fig. 7 is a perspective of one end of the tie illustrated in Figs. 4, 5 and 6.

40 Fig. 8 is a detail perspective of one of the filler blocks adapted to be used in connection with the tie, illustrated in Fig. 7. Fig. 9 is a perspective view of the filler block adapted to be used in connection with the chair illustrated in Fig. 3. Fig. 10 is a detail perspective of one of the rail engaging spikes.

45 By referring to the drawings it will be seen that 1 designates the tie which is of an I-beam structure having the upper flange 2 thereof constituting a head portion for supporting the rails and chairs adapted to be carried by the tie 1. The tie also comprises a broad base portion 3 constituting an efficient support for the tie 1.

50 As is illustrated in Figs. 1, 2 and 3 a de-

tachable chair or rail support is adapted to be secured to the tie 1 and comprises a body portion 4 having a pair of parallel downwardly extending lips 5, which lips 5 are adapted to engage the vertically extending portion of the tie 1. The body portion 4 of the chair is provided with laterally extending pockets 6 in which pockets is adapted to fit the flange portion 2 of the tie 1. 60 The body portion 4 of the chair is also provided upon the top thereof with an opening 7 and a pocket 8, which pocket 8 is adapted to receive the filler block 9, which tread block is adapted to engage the under face of the rail 10 placed upon the chair 4. The body portion of the chair is also provided upon the side edges thereof with a pair of laterally extending flanges 11, which flanges are spaced from the body portion to constitute channel portions 12. The flange portions 11 are provided with notches 13, which notches 13 receive the securing spikes or rail engaging members 14 for firmly holding the rail 10 in engagement with the chair. It 70 will be understood that the nuts 16 which are threaded upon the lower threaded end 17 of the rail securing members 14 are held within the channel portion 12 and will in this manner be protected against engagement with foreign objects which would be likely to cause the nuts to be unthreaded from the threaded portion 17 of the rail engaging bolts 14. The depending flange portions 5 of the chair are held in engagement with the vertically extending portion of the tie 1 by means of the transversely extending bolts 18 as is illustrated clearly in Fig. 2.

45 As is illustrated in Figs. 4 to 7 inclusive 95 a modified means for attaching a rail to the tie, as is illustrated in Figs. 1 and 2, may be employed by having the tie 18' of the substantially I-beam structure, and this tie 18' is provided with a head portion 19 and a 100 base portion 20. The head portion 19 is provided with a notch 21, which notch is also provided with a pocket 22 formed therein. A thickened portion 23 is formed under the notch 22 under the edge of the head portion 105 19 so as to constitute an efficient reinforcing means for the head of the tie 18' at the point where the rail 24 is supported thereon. A plurality of apertures 25 are formed upon the head 19 of the tie 18' for the purpose 110 of receiving the rail engaging bolts 26 as is clearly illustrated in Fig. 5. The lower ends

of these rail engaging members are threaded as indicated at 27 for receiving the nut 28, and this nut is held against downward movement upon the bolt by means of the cotter pin 29. A washer 30 is interposed between the lower face of the head 19 and the nut 28, thereby constituting an efficient means for holding the rail engaging members 26 in firm engagement with the rails 24. It will be seen from the foregoing description that the nuts 28 will fit under the head portion 19 of the tie 18 and upon either side of the thickened portion 23 adapted to fit under the tread of the rail 24 and in this manner will be protected against engagement with foreign objects which would be likely to cause the nuts to become unthreaded. A filler block 31 is seated in the pocket 22 and constitutes a support for the base of the rail 24 as is illustrated in Fig. 5.

From the foregoing description it will be seen that a very simple and efficient means has been produced for attaching a rail and efficiently holding the same in engagement with a tie.

Having thus described the invention what is claimed as new, is:—

1. In a device of the class described the combination with a tie comprising a base portion and a head portion, said head portion provided with means for receiving a rail, rail engaging members carried by said tie and adapted to engage a rail for holding a rail in firm engagement with said tie, means threaded upon the lower ends of said rail engaging members for preventing the accidental removal of said rail engaging members from said tie, said rail receiving portion of said tie provided with a pocket,

46
a block positioned within said pocket and adapted to support the base of a rail, and said rail receiving portion adapted to constitute means for protecting the lower ends of said rail engaging members to prevent the accidental removal of the rail engaging 45 members from said tie.

2. In a device of the class described the combination with a tie comprising a substantially I-beam structure, of a chair comprising a body provided with parallel downwardly extending flanges adapted to engage the vertical portion of said tie, said chair provided with laterally extending pockets adapted to receive the head portion of said tie, said chair provided with a block receiving pocket, a filler block positioned within said pocket and adapted to engage the under face of the base of a rail, said chair provided with laterally and longitudinally extending flanges formed upon the sides thereof, said flanges being spaced from the body portion of said chair to constitute channel portions, said flanges provided with notches, rail engaging clips fitting within said notches and engaging a rail for holding the rail in firm engagement with said chair, said rail engaging lips provided with threaded ends, and nuts threaded upon said rail engaging lips and fitting within said channels whereby said nuts will be held from engagement with foreign objects.
